UNITED STATES PATENT OFFICE.

BRADFORD LESLIE, OF LONDON, ENGLAND.

DRAWBRIDGE.

1,078,293.

Specification of Letters Patent. Patented Nov. 11, 1913.

Application filed January 24, 1912. Serial No. 673,102.

To all whom it may concern:

Be it known that I, BRADFORD LESLIE, K. C. I. E., a subject of the King of Great Britain, residing in London, England, and whose 5 post-office address is 5 Chester Gate, Regents Park, in the county of London, England, engineer, have invented a certain new and useful Improvement in a Drawbridge, of which the following is a specification.

10 Suspended folding drawbridges hitherto constructed have always been made with the inner leaf articulated to the abutment and with the points of suspension of the leaves at the ends thereof. This construction has 15 the disadvantage that the whole weight of the leaves has to be lifted and the consumption of power is considerable. To overcome this objection the inner leaf has been pivoted to the abutment at a point between its 20 ends so as to form a lever, the free end of which carries a counterweight. In this case there is the disadvantage that the rigidity of the girder composed of the two leaves is considerably reduced; moreover the total 25 length of the bridge has to be increased by the portion extending beyond the abutment over the shore.

The present invention provides a suspended drawbridge wherein when the bridge is 30 being opened or closed the two leaves balance each other substantially completely, in such manner that their common center of gravity travels inward horizontally, if there is sufficient clearance above the water or if 35 there is not sufficient clearance to avoid immersion of the leaves in the water when they are in the folded position, the balance may be partial, in which case the common center of gravity rises. The construction may be 40 such that when the clearance between the road or rail and the water is not less in depth than say 25 per cent. of the length of the bridge or the half-span the leaves may be folded or extended without substantial 45 alteration of the level of their common center of gravity. When the clearance is less than this, it becomes necessary to raise the common center of gravity when raising the bridge, by an amount inversely proportional 50 to the clearance available. The leaves are supported by chains from pillars or the like, on the abutment without other attachment to the abutment, the points of suspension being so located that the portions of the leaves 55 external to such points partially balance the portions between the points; the free end

of the inner leaf rests against the abutment but free thereof, so that as soon as the locking device, which holds up this end when the bridge is closed, has been withdrawn, this 60 inner end travels downward, thus raising the hinge that connects the two leaves above the line of thrust of the compound girder and making it possible to lift the leaves by a small expenditure of power.

65 The accompanying diagrams illustrate the invention.

Figure 1 represents a side elevation of the half-span of a bridge the height of which above the water level A—A is more than 25 70 per cent. of the length of the half-span, and Fig. 2 a side elevation of the half-span when the height is less than this. Fig. 3 is an enlarged view of the lower right hand portion of Fig. 1.

75 Referring to Fig. 1, the platform of the bridge is carried between a pair of side girders each composed of two substantially equal parts *a*, *a'*, the lower members of the girders constituting these parts, which may 80 conveniently be called outer and inner leaves respectively, being hinged together as at *a*². When the leaves are extended as shown in the drawing the upper members of the girders abut against each other. The girders 85 are suspended by chains *b* *b'* in a suitable manner from a pair of pillars or other appropriate support *c* erected on the abutment and properly stayed according to well-known engineering practice. These chains support 90 the dead-weight of the drawbridge as well as the live load, and when extended the drawbridge forms the bottom member of a suspended cantaliver.

95 When the leaves are extended their centers of gravity are between the points of suspension of the leaves from chains *b* *b'*, the distances of these points from the centers of gravity depending on the height of lift required. The horizontal component of the 100 force sustaining the extended leaves is a pressure transmitted through the girders to the abutment. The line of this thrust is above the hinge *a*²; in order to fold the leaves the hinge must be raised above the 105 line of pressure. For the purpose, the inner ends of the girders carry rollers *d* which, in the extended position of the leaves, rest against the upper end of concavely curved roller paths *e* made in the abutment or otherwise provided. The curvature of the roller path is such that the horizontal thrust would 110

cause the roller to travel down the path were it not prevented by a suitable lock, such as the arm *f* of a shaft *g*; this arm extends beneath the inner end of the inner leaf *a'* 5 and supports the latter. When it is desired to fold the leaves, the shaft *g* is turned, it may be by means of a worm *h* and a toothed quadrant *i*, until the arm *f* is removed from beneath the end of the girder. The roller 10 now travels down the path and both the leaves turn about their points of suspension from chains *b*, *b'* so that the hinge *a²* rises, say to the dotted position *a³*. This automatic movement continues until a position 15 of equilibrium is attained, in which position the leaves make substantially equal angles with the vertical through the hinge *a²*. It now becomes possible to fold the leaves by applying sufficient lifting force to balance 20 the excess weight of the leaves at the hinge and thus to cause the roller to continue its movement down the path. Any convenient mode of applying this force may be adopted. In Fig. 1 there is shown an oscillating derrick *h* stepped in front of the support *c*; the 25 end of this derrick is connected on the one hand with a toothed segment *l* and on the other hand, by means of a spar *k'*, with the hinged end of the leaf *a*. The segment *l* is engaged by a pinion *m* driven, for instance, by an electric motor; the segment carries a 30 pair of wheels *n* which travel on a fixed path *o*.

It is an object to keep the two leaves balanced as far as possible during the operation of folding or extending, and to this end the leaves should remain throughout the operation at substantially the same inclination to the vertical through hinge *a²*. The point of 35 suspension of the chain *b'* to the supporting pillar is such that when the leaves are completely folded, as indicated in dotted lines, the chain is vertical, in this position it carries the weight of both leaves and the roller 40 *d* is at the bottom of its curved path. The inclination of the leaf *a'* during the operation of folding depends on the rotation of the leaf about its point of suspension to the chain as this swings into the vertical position 45 and roller *d* travels down its path. To preserve the desired inclination of the leaf *a*, there is provided a collapsible strut *p* normal to the leaf and supporting the chain *b* at a certain distance from the attachment of 50 the chain to the leaf. The length and position of the strut are such that during the folding of the leaves and also when these are in the vertical, folded position, the chain *b* continues to carry the weight of leaf *a* 55 and finally counteracts the tendency of the folded leaves to fall outward consequent on the center of gravity being outside the point of suspension of the inner chain. When the leaves have attained the vertical, folded position, the inner leaf *a'* is caught by a catch 60

such as hook *q* and the collapsible strut may then be folded, whereupon the chain *b* ceases to support any of the weight and hangs loosely against the leaf *a*. The strut may consist of two parts pivoted together as at 65 *p'*, one part being pivoted to the chain *b* and the other part to the girder *a*; as a means for collapsing the strut, the latter part may carry a toothed sector *r* engaging a pinion *s* adapted to be turned by a hand 70 wheel. 75

To extend the leaves, the strut *p* is opened and the locking hook *q* raised. The power being disconnected, the leaves then fall into the position of equilibrium, that is until the 80 hinge *a²* approaches the line of horizontal thrust. Then the raising of lever arm *f* brings the leaves into the fully extended position. Or the power may be applied through the spar *k'* for pressing the leaves 85 into the extended position.

In Fig. 2 the general arrangement is similar to that described with regard to Fig. 1 and the same reference letters are used to indicate like parts. As, however, the bridge 90 is much nearer the water and the leaves must be lifted clear of the water, the points of suspension from the chains *b*, *b'* must be correspondingly farther from the center of gravity of the leaves. This entails a much 95 larger proportion of unbalanced weight at the hinge *a²* and the common center of gravity has to be raised considerably instead of moving in a substantially horizontal line. In order to enable the bridge to be operated 100 with about the same expenditure of power as in the case of Fig. 1 the aforesaid unbalanced weight is counterbalanced by weight *t* connected by link *u* with the segment *l* and provided with wheels to travel on the incline *v*. The curved path *e* is correspondingly shorter than that shown in Fig. 1. It 105 may be added that the curvature of this path may be experimentally determined for each case. When the two leaves constitute the 110 whole span of the bridge, part of the live load may be carried by the opposite abutment.

Having thus described the nature of the 115 said invention and the best means I know of carrying the same into practical effect, I claim:—

1. A folding drawbridge comprising an abutment, pillars on the abutment, an inner leaf having its inner end resting against but 120 separate from the abutment, and an outer leaf hinged to the outer end of the inner leaf, the said leaves being suspended from the said pillars without other pivotal attachment to the abutment and at points intermediate of their ends, in a manner to allow 125 them to turn about their points of suspension.

2. A folding drawbridge comprising an abutment, pillars on the abutment, an inner 130

leaf having its inner end resting against but separate from the abutment, and an outer leaf hinged to the outer end of the inner leaf, the said leaves being suspended 5 from the said pillars without other pivotal attachment to the abutment, the points of suspension being intermediate of the ends of the leaves and in such positions that the portions of the leaves external to the said 10 points partially balance the portions between the points.

3. A folding drawbridge comprising two leaves, each hinged to the other at one end, an abutment, pillars on the abutment, chains 15 suspending the outer leaf from the said pillars and chains suspending the inner leaf from the said pillars, the points of attachment of the said chains to the said leaves being so located that the portions of the 20 leaves external to the points partially balance the portions between the points, means for locking the said leaves in extended end to end position, means for releasing the said means, means for applying power to fold the 25 bridge and means for reducing the effective length of the chains suspending the outer leaf correspondingly as the leaf folds against the inner leaf.

4. A folding drawbridge comprising two 30 leaves, each hinged to the other at one end, an abutment, pillars on the abutment, chains suspending the outer leaf from the said pillars and chains suspending the inner leaf from the said pillars, the points of attachment 35 of the said chains to the said leaves being so located that the portions of the leaves external to the points partially bal-

ance the portions between the points, means for locking the said leaves in extended end to end position, means for releasing the said means, means for applying power to fold the bridge, and struts pivoted at one end to the chains suspending the outer leaf and attached at the other ends to points in the outer leaf between the points of attachment 40 of its suspending chains and the hinged end of the leaf. 45

5. A folding drawbridge comprising two leaves, each hinged to the other at one end, an abutment, pillars on the abutment, chains 50 suspending the outer leaf from the said pillars and chains suspending the inner leaf from the said pillars, the points of attachment of the said chains to the said leaves being so located that the portions of the 55 leaves external to the points partially balance the portions between the points, means for locking the said leaves in extended end to end position, means for releasing the said means, means for applying power to fold the 60 bridge, and folding struts pivoted at one end to the chains suspending the outer leaf and attached at the other ends to points in the outer leaf between the points of attachment of its suspending chains and the hinged end 65 of the leaf.

In testimony whereof I have signed my name to this specification in the presence of two subscribing witnesses.
